to Fuel Refining Corporation, Dover,
Del., a corporation of Delaware

Application December 8, 1937, Serial No. 178,707
In Germany December 28, 1936

13 Claims. (Cl. 202—248)

The general object of the present invention is to provide coke oven doors and particularly self-sealing doors for horizontal coke ovens, with improved means for releasably locking the doors in their closed positions. More specifically stated, the object of the invention is to provide a coke oven door with simple and effective door locking means, characterized by their novel construction and capacity for automatic actuation by the door handling mechanism to lock the door in place at the end of a door closing operation, and to unlock the door at the beginning of a door opening operation.

In accordance with the present invention, the hooks carried by the stationary doorframe, or other door retaining devices, are engaged in the locked condition of the door by the locking bars or elements carried by supports mounted on the door for movement relative thereto in the direction of the axis of the door. Each such support is adapted to be bodily adjusted axially of the door, to correspondingly adjust the corresponding door locking element, by a vertically moving cam element, mounted on the door and adapted to be given vertical movements by the door handling mechanism employed to remove and replace the door. In the usual case, in which there are two locking bar supports mounted on the door, the corresponding support adjusting cams are connected by a link for simultaneous actuation by the door handling mechanism.

In the use of our present invention in self-sealing coke oven doors, we advantageously provide resilient means acting between the door and its locking means, whereby in the locked position of the door, the sealing element of the door is pressed against the sealing surface on the door seat, with a suitable pressure and depending on the spring corresponding to force or tension of said resilient means. In preferred forms of the present invention, the locking elements are adjustable relative to their supports to vary the sealing pressure due to said resilient means in the locking position of the door, and also to suitably secure in place and release the door, in case of failure of said resilient means. The cams may be actuated in one direction by the door machine to unlock the door and may be returned, when the door machine permits, by spring or gravitational action.

In accordance with the present invention, the said resilient means may act between the locking bar supports and the door in the direction to press the locking bar against the retaining hooks when the door is in its locked condition, so that

the resilient means is compressed and has its tension increased by the action of the door machine unlocking the door. Alternatively, the resilient means may be inserted between the locking elements and their supports, and in this case the coacting cams act to increase the spring tension in locking the door in place, and to decrease the spring tension as the door is unlocked. In the last mentioned arrangement, an additional weak spring may be employed to move the locking bar support toward the door as the door is unlocked.

In some cases, the hook engaging portions of the locking bars need not be vertically movable relative to the door, being then moved into and out of engagement with the hooks by the corresponding vertical bodily movements given the door by the door machine. When the extent of vertical door movement required for operation in the manner just mentioned is undesirable, it may be avoided by pivoting each locking bar to turn relative to the door about a horizontal axis into and out of engagement with the retaining hook. Such turning movements of the locking members may be automatically effected by the door machine, when the latter is provided with known expedients for the purpose.

For a better understanding of the invention, reference should be had to the accompanying drawings and descriptive matter in which we have illustrated and described preferred embodiments of our invention.

Of the drawings:

Fig. 1 is a partial vertical section of a coke oven battery, taken on the line 1—1 of Fig. 2; 35

Fig. 1a is a fragmentary view taken similarly to Fig. 1, and showing the door locking parts in positions different from those shown in Fig. 1;

Fig. 2 is an elevation of a portion of a coke oven door and doorway shown in Fig. 1; 40

Fig. 3 is a section on the line 3—3 of Fig. 2;

Fig. 4 is an elevation taken at right angles to Fig. 3, illustrating the relative arrangement of a door retaining hook and locking bar in the locked position of the door; 45

Fig. 4a is a view similar to Fig. 4, but with the locking bar moved inwardly out of locking engagement with the locking hook;

Fig. 5 is a section taken similar to Fig. 1, illustrating a coke oven door having a modified locking construction; 50

Fig. 5a is a view taken similarly to Fig. 5, but on a larger scale and showing a portion only, of the construction shown in Fig. 5;

Fig. 5b is a section taken on the same plane 55

as Figs. 5 and 5a, but on a larger scale than Fig. 5a, and showing a portion only of what is shown in the last mentioned figure;

Fig. 6 is a section on the line 6—6 of Fig. 5;

5 Fig. 7 is a section similar to Fig. 1, taken on the line 7—7 of Fig. 8, and illustrating a second modification of the invention;

10 Fig. 7a is a fragmentary view taken similarly to Fig. 7, with parts shown in different relative positions;

15 Fig. 7b is a side elevation, on a larger scale than Fig. 7, of one of the clamping cams shown in Fig. 7;

Fig. 8 is an elevation of a portion of the door 20 and door-frame shown in Fig. 7; and

Fig. 9 is a section on the line 9—9 of Fig. 8.

In the known type of door and door-frame construction illustrated, the coke oven door comprises a rigid outer frame or supporting section, 25 a flexible sealing member, and an inner plug section. The outer section includes main vertical channel bar members 1, and horizontal connections between said members, one of the latter being shown in cross section in Fig. 3, as comprising the hereinafter mentioned guide member 12. The sealing member comprises a flexible plate 2 extending across the doorway and formed with a marginal sealing rim or edge 3, adapted to engage and make a gas-tight joint with a sealing surface 4' on a door-frame 4 surrounding the 30 mouth of the oven chamber with which the door is associated. The outer door section supports the flexible sealing member of the door, through connecting means which need not be illustrated or described since they may be of known form, such, for example, as that shown in the Otto U. S. Patent 1,827,329. Adjustable clamping connection 2' which may be of any usual or suitable form, transmit pressure from the outer door 35 section to the marginal portion of the sealing member. The brickwork 6 of the plug section of the door rests upon a supporting shoe 5, connected in a known manner to, and directly supported by the sealing member 2.

40 As shown, the door is secured in place by upper and lower horizontal locking bars 7, each of which, in the closed and locked condition of the door has its ends in engagement with door retaining hooks 8, secured to the opposite sides of 45 the door-frame member 4. Each locking bar 7 is mounted on a corresponding support which as shown in Figs. 1-3, comprises a horizontal bolt 9 extending in the axial direction of the door midway between the sides of the latter, and a supporting body or cross head 10 in threaded engagement with the bolt 9. The body 10 is mounted for sliding movement in the axial direction of the door in a guide way formed in the previously mentioned guide member 12. Each 50 bolt 7 extends through and is so mounted in the corresponding locking bar, that the bolt may be rotated relative to the bar, but is not movable relative to the latter in the direction of its length. A spring 11, acting between each guide 12, and 55 the inner end of the corresponding support 10, tends to move the latter outwardly, so that with the door in its closed position, the ends of the corresponding locking bar are pressed outwardly against the retaining hooks 8, and the sealing 60 rim 3 of the door is correspondingly pressed inwardly against the door frame member. Each locking bar 7 is prevented from rotating about the axis of its supporting bolt 7, by angular parts or projections 36 carried by the channel bars 1.

70 75 The upper and lower locking bar supports are

adapted to be retracted into their guides 12, by cam members 13 and 13a, respectively. The cam members 13 and 13a differ from one another only in that a connecting link 14 is connected to the lower end of the upper cam 13 and to the upper end of the lower cam 13a. Each of said cams extends through slots formed in the corresponding supporting body 10, and guide 12, and is in effect a wedge acting between upper and lower parts 16, carried by the guide member 12 at the front or outer side of the cam, and a roller 15 carried by the support 10 in position to be engaged by the inner or rear edge of the cam 13 or 13a. The parts 15 and 16, as shown, are anti-friction rollers mounted to turn about horizontal axes transverse to the door axis.

As shown, the door handling mechanism comprises an arm 17, the free end of which is given up and down movements in removing and replacing the door. Adjacent its free end, the arm 17 is 20 formed with a notch 18 at its upper side, adapted to receive a part 19 rigidly connected to channel bars 1, when the arm 17 is raised, whereby, the door is lifted by the arm 17, as the latter continues to move upward after the part 19 engages the bottom wall of the notch 18. Prior to the operative engagement of the arm 17 with the door part 19, the bifurcated ends 20 of the arm 25 projections or shoulders 21 of the link 14, and thereby raise the cams 13 and 13a, so that by 30 the time the arm 17 operatively engages the lifting part 19 and starts to lift the door, each locking bar 7 has been retracted as shown in Fig. 4a, by the action against the corresponding roller 15 of the corresponding cam 13 or 13a. After the 35 door has been raised sufficiently to move the ends of the locking bars 7, above the hooks 8, the door handling mechanism may be manipulated in the usual manner to move the door out of the doorway and then laterally of the latter.

40 In the door replacing operation, the door parts are returned to the positions illustrated in Fig. 4a, and thereafter, as the arm is lowered to transfer the weight of the door from the door handling mechanism to the door frame, the cams 13 and 45 13a are lowered to permit movement of the locking bars outwardly into operative engagement with the hooks 8 as shown in Fig. 4. The down movement of the cams 13 and 13a may be effected positively by the door handling mechanism, but 50 advantageously, and as shown, the cams 13 and 13a are biased for down movement. To this end the effect of the weight of the cams and link 14 is supplemented by the action of a spring 22, which acts between a nut secured to the lower end 55 of the cam 13a, and a transverse portion of the rigid outer section of the door.

60 In effect, each bolt 9 and its support 10 forms both a sliding support for the corresponding locking bar, and a strut through which the spring 11 acts on the corresponding locking bar 7, to force the latter outwardly against the hooks 8, and to force the sealing rim 3 against the sealing surface on the door frame 4, with a sealing pressure dependent on the sum of the tension forces 65 tending to elongate the two springs 11 of the door. The effective length of said strut may be varied, and the normal sealing pressure increased or decreased, by screwing the bolt 9 further into, or out of its supporting body 10. To 70 facilitate this screw-adjustment, the outer end of the bolt 9 is squared for wrench engagement as indicated at 23. In the case of a failure of a spring 11, the corresponding bolt 9 may be manually threaded out of its support 10, far enough 75

to positively lock the door in place and establish the proper sealing pressure. By reverse rotation of the bolt, the door may be manually unlocked.

3 In the normal contemplated operation of the apparatus shown in Figs. 1 to 4a, when the door is in its closed and locked condition, with each locking bar 7 in operative engagement with the corresponding hook 8, as shown in Fig. 4, the
10 cams 13 and 13a are lowered far enough to be out of thrust transmitting relation between the roller 15 and the roller 16. However, by making the upper portions of the inner and outer edges of each of the cams 13 and 13a parallel, said
15 upper cam portions may act as stops, limiting the outward movements of the rollers relative to the rollers 15 under the springs 11, regardless of the exact vertical positions of the cams. In such case, the total pressure between the two
20 locking bars 7 and the corresponding members 8 cannot exceed the sum of the spring forces opposing the contraction of the two springs 11, when the parallel portions of the cams 13 and 3a are engaged by the rollers 15 and 16, and said
25 pressure may be variably reduced by threading the bolts 9 into their respective supports 10.

In the form of the invention shown in Figs. 5, 5a, 5b and 6, the locking bars 7 are mounted on supports, each comprising an outer bolt portion 26 threaded into a cross head like part 27, substantially like the locking bar supports formed by the previously mentioned parts 9 and 10. In Figs. 5-6, however, each part 27 is slidably received in a support 24, which is pivotally connected by pivots or bolts 25 to the channel bars 1. The supporting pivots 25 for each member 24 are located at some distance above the corresponding part 27, and a spring 28, corresponding operatively to the previously mentioned springs 11, acts between the inner end of each part 27, and the corresponding member 24, and, when under compression tends to turn said member 24 counter-clockwise about its pivots 25. Each part 27 is in splined relation with the support 24, so that it cannot share the rotative movements of the bolt 26, when the latter is rotated for adjustment purposes.

In the normal locked position of the door shown in Figs. 5-6, the supports 24 are held in their positions shown in Fig. 5, and in the door unlocking operation, the parts 24 are permitted to turn counterclockwise to relieve the locking pressure between the locking bars 7 and retaining devices 8 and to relieve the sealing pressure between the sealing edge 3 and door frame surface 4'. The upper locking bar is shown in its released position in Fig. 5A. The upper support 24 is moved between its position shown in Figs. 5 and 5A, and the lower support 24 is similarly moved, as a result of vertical movements which the door handling mechanism arm 17 gives to an actuator, as movements are given to the link 14 and cams 13 and 13a of the construction first described. In the particular arrangement shown, the actuator of Figs. 5-6 is a vertical I beam having its web 29 transverse to the door axis and extending upwardly above, and downwardly below, the upper and lower ends, respectively, of the I beam flanges 30, connected at the opposite edges of the web 29. The means through which the up and down movements of the I beam give turning movements to the support 24, comprise a thrust element acting between each member 24 and an abutting element 35, secured to the channels 1. Each thrust element comprises a pair

of rollers 31 and 33, at the inner and outer sides, respectively, of the web 29, and having their ends journalled in transverse bar like parts forming the end members of a sliding frame 32. In the locked condition of the door, the rollers 31 and 33 are frictionally held between the web 29 and the adjacent sides of the corresponding members 24 and 35, respectively. On an up movement of the web 29, the rollers 31 and 33 are caused to rotate, and are moved upward with half the vertical velocity of the web 29. The upper portions of the adjacent sides of the parts 24 and 35 diverge, so that the up movements of the thrust members 31—3, permit counterclockwise movement of the parts 24, whereby the locking and sealing pressures are released. As shown, the upper ends of the flanges 30 are adapted to engage the upper sliding frame 32 and parts 34 secured to the web 29 below the lower sliding frame 32, are adapted to engage the latter, if, as a result of slippage, the sliders do not move upward as contemplated when the web 29 is raised. The web 29 might carry provisions for positively engaging the sliding frames and moving the latter downward, but with the gravitational tendency of said frames for down movement, the last mentioned provisions are ordinarily unnecessary.

In the modified arrangement shown in Figs. 7-9, guide members 39 secured to the outer door section channels 1, and generally similar to the guides 12 of the construction first described, receive sliding supports 37, into which locking bars supporting bolts 37' are threaded. A compression spring 38 acts between the outer end of each support 37 and the corresponding locking bar 1, tending to move the latter outward into engagement with its retaining hooks 8. Each support 37 is slotted for the passage of a corresponding vertically movable upper cam 42 or lower cam 40 42a. The outer edge of each of said cams engages a roller 41, carried by the corresponding support 37. The rear edge of each cam engages two rollers 40, carried by the support 39.

In its lower position shown in Fig. 7a, each of the cams 42 and 42a engages the corresponding roller 41 and holds the latter in its outer position, in which the corresponding spring 38 is compressed and establishes the proper locking pressure between the corresponding locking bar 45 and hooks 8, and sealing pressure between the sealing edge 3 and door frame surface 4'. When the cams 42 and 42a are raised into the position shown in Fig. 7, the rollers 41 are permitted to move inwardly and thus relieve the compression of the springs 38. As shown, springs 48 are provided to pull the supporting members 37 inwardly and thereby move the end of the locking bar inwardly away from the hooks 8, when the cams 42 and 42a are raised to relieve the tension of the springs 38. For their intended purpose, the springs 48 may be light, or weak, in comparison with the springs 38. The two cams 42 and 42a are connected by a link 43 provided with projections 46 and 47, between which the forked ends 44 of the door handling arm 45, may enter as shown in Fig. 7. The cams 42 and 42a are thus positively moved relative to the door, up and down, as the arm 45 is respectively moved up into and down from its position of operative engagement with the door part 19 through which arm raises the door, the latter is moved upward to engage the door part 19 and lift the door.

As shown, the upper portions of the inner and outer edges of the cams 42 and 42a are parallel, 75

so that in initial down movement of each cam subjects the corresponding spring 38 to the full compression force to which it is to be subjected, and further down movement of the cams has no effect on the compression of the spring. This makes it possible to insure the proper sealing pressure, prior to the completion of the full down movement relative to the door given the cams 42 and 42a by the door handling mechanism. As shown, the right hand edges of the cams 42 and 42a are vertical, and the lower portion of the left hand edge of each cam is inclined to the vertical, so that the cam is in effect a wedge. The inclination to the vertical of the lower portion of the left hand edge of each cam may be diminished as the distance from the lower end of the cam increases, so as to reduce the ratio of compression stress of the corresponding spring 38 to the resultant force opposing the down movement of the corresponding cam, as said stress is increased in the door locking operation. Such a variation in the wedge action, to minimize the maximum resistance to wedge movement, may be employed with the constructions previously described. It will be apparent, also, that with the arrangement shown in Figs. 7-9, as with those shown in the other figures, it is immaterial whether the locking bar actuation is due to the location of a cam surface, is due to the inclination to the vertical of a cam surface at the front or the rear of the vertically movable actuator or is due to inclined cam surfaces at each side of the actuator.

With the arrangement shown in Figs. 7-9, as with those previously described, the rotation of each locking bar bolt relative to the supporting sleeve with which it is in threaded engagement, adjusts the normal sealing pressure, and also permits the doors to be manually locked in place and released in case of failure of the sealing pressure springs.

As those skilled in the art will understand, changes may be made in the form of the apparatus disclosed herein without departing from the spirit of our invention as set forth in the appended claims, and in some cases, use may advantageously be made of some features of the invention, without a corresponding use of other features.

Having now described our invention, what we claim as new and desire to secure by Letters Patent, is:

1. A coke oven door comprising in combination a door adapted to engage the door seat of a coke oven structure having a door seat and door holding means associated with said seat, of a locking member mounted on said door for movements toward and away from the latter into and out of operative engagement with said holding means, cam means mounted on said door and including an actuating member mounted on said door for bodily vertical movement relative thereto and adapted to be moved vertically by a vertically moving door machine part and a spring, said spring and cam means collectively forming a mechanism adapted to establish or eliminate a resilient force action between said locking member and door tending to move them apart, accordingly as said member is bodily moved in one vertical direction or the other.

2. A coke oven door as specified in claim 1, in which the said spring is disposed to act between said door and locking member to move the latter away from the door when said spring is free to expand, and in which said cam means

acts on said spring to compress it, or to permit it to expand accordingly as said actuating member is moved bodily in one vertical direction or the other.

3. A coke oven door as specified in claim 1, in which said spring is a compression spring disposed to act between said locking bar and cam means, whereby said spring is compressed by said cam to establish the resilient force tending to move said locking bar and door apart. 10

4. A coke oven door as specified in claim 1, in which said spring is a compression spring disposed to act between said locking bar and cam means, whereby said spring is compressed by said cam to establish the resilient force tending to move the last mentioned locking bar and door apart, and in which a spring weaker than the first mentioned spring is mounted on said door and is adapted to move said bar toward said door when the first mentioned spring is not compressed 20 by said cam.

5. A coke oven door as specified in claim 1, in which said locking member is mounted on a support comprising a member movable in a direction parallel to the door axis and also comprising a bolt extending in said direction and in threaded engagement with the last mentioned member, and interposed with said spring and cam means between said door and locking member. 25

6. A coke oven door as specified in claim 1, in which said locking member is mounted on a support comprising a member movable in and extending in a direction parallel to the door axis and adjustable in length and forming a strut 35 interposed in series with said spring and cam means between said door and locking member.

7. A coke oven door as specified in claim 1, in which said locking member is carried by a support comprising a bolt extending in the axial 40 direction of the door and a supporting body movable relative to the door in the axial direction of the latter and formed with a threaded socket into which said bolt is threaded, and in which said bolt extends through and is rotatable, but 45 not axially adjustable relative to said member, and in which said spring and cam means act on said locking member through said supporting body.

8. A coke oven door as specified in claim 1, comprising a supporting member formed with a guideway extending in the general direction of the axis of the door, and pivotally connected to the latter to turn relative thereto about an axis vertically displaced from said guideway, and in which a part axially movable in said guideway directly supports said locking member, and in which said spring acts between the first mentioned member and said door in a direction to move said locking member away from the door, and in which said cam means act between said door and supporting member. 50

9. A coke oven door as specified in claim 1, comprising a supporting member formed with a guideway extending in the general direction of the axis 55 of the door, and pivotally connected to the latter to turn relative thereto about an axis vertically displaced from said guideway, and in which a part axially movable in said guideway directly supports said locking member, and in which said spring acts between the first mentioned member and said door in a direction to move said locking member away from the door, and in which said cam means act between said door and supporting member, and comprises a pair of spaced 60 70 75 80 85 90 95 100

apart horizontal rollers interposed between said supporting member surface and a door surface, and a vertical and vertically movable bar extending between said rollers.

5 10. A coke oven door as specified in claim 1, and including means for biasing said actuating member for movement in one vertical direction and in which said actuating member is adapted to be moved in the opposite direction by the door machine.

11. A coke oven door as specified in claim 1, in which the said actuating member is a wedge acting between said locking member and door and adapted to effect movement of said locking 15 member toward and away from said door accordingly as it is moved in one vertical direction or the other.

12. A coke oven door as specified in claim 1, in which the said actuating member comprises 20 a wedge portion having inclined edge portions adapted to act between said locking member and

door in one portion of the range of movement of said actuating member and effect movement of said locking member toward and away from said door accordingly as said wedge portion is moved in one vertical direction or the other, and comprising a second portion in end to end relation with its said wedge portion and having parallel edge portions adapted in another portion of the range of movement of said actuating member, to act between said locking member and door 10 and maintain said resilient force constant.

13. A coke oven door as specified in claim 1, in which the said actuating member is a vertically disposed wedge varying in taper along its length and acting between said locking member and door and adapted to effect movement of said locking member toward and away from said door accordingly as it is moved in one vertical direction or the other.
